THEODORE SCHMITT, OF CLEVELAND, OHIO

SUPPORTING DEVICE AND METHOD OF FORMING THE SAME

Application filed June 13, 1929. Serial No. 370,524.

This invention is concerned with a device particularly adapted for supporting elements used in concrete construction, which elements are required to be disposed a comparatively short distance above an adjacent surface, and with a method of making such devices.

In building floors, beams, etc., largely of concrete, some reinforcement for the concrete is necessary, and the most commonly known reinforcement is provided by spaced steel bars which should be maintained in proper relation to each other to give the desired strength to the concrete. The concrete is filled in around the bars, being supported in suitable false-work until it hardens.

Where long horizontal stretches of concrete are used, as in beams and joists for example, the reinforcing bars act as the primary tension elements to lend strength to the concrete structure, and these are usually placed, for the most part, in the bottom portions of the joists or beams close to the bottommost surface. It is highly essential that the bars be spaced uniform distances from each other, as well as uniform distances above the false-work, so as to prevent weak points in the beam structure and to prevent the bars from being exposed when the false-work is removed. The concrete should, for example, afford a complete sheath for all portions of the bars so as to insure the bars against corrosion for long periods of time.

My invention contemplates forming low lying chair supports for concrete reinforcing bars and the like, which chairs shall be extremely inexpensive, adequately strong, and unlikely to become tipped over while the bars are being put into place in the false-work.

An object of the invention is to provide a chair which may be easily and economically made from a single piece of inexpensive metal stock. More specifically, an object is to provide a one-piece chair structure adapted to be made from suitable gauge wire, wherein sharp angles or bends are eliminated. Such sharp bends ordinarily render the devices of this character previously used, difficult to make and weak by reason of the strain on the metal due to such sharp bends.

A further object is to provide a one-piece chair adapted to be made from elongated metal stock, such as wire, wherein close loops are eliminated.

A further object is to provide a one-piece metal reinforcing bar chair which will have unusual vertical strength, considering the cross section of the stock used, and which will at the same time provide for spacing a plurality of bars accurately to thereby prevent weakening the concrete structure by non-uniform spacing.

Another object is to simplify the construction of concrete reinforcing bar chairs while maintaining adequate strength, to thereby reduce the cost thereof to the builder.

A further object is to provide a novel and effective method of producing an article, such as herein shown and described, which will decrease the cost of manufacture as compared to previous methods of making similar articles, without weakening the metal of the article.

Further objects and features of the invention will become apparent from the following description relating to the accompanying drawings which illustrate the preferred form of device and method of making it. The essential novel characteristics are summarized in the claims.

In the drawings, Fig. 1 is a perspective view of the chair showing the manner in which reinforcing bars are adapted to be supported thereon; Fig. 2 is a side elevation of the chair shown in Fig. 1 and showing diagrammatically bars of different cross sectional character from those shown in Fig. 1; Fig. 3 is an end elevation of the chair; Fig. 4 is a cross sectional view taken along the line 4—4 in Fig. 2, and Figs. 5, 6, 7 and 8 illustrate diagrammatically the more essential steps in producing the chair by the preferred method.

The character of reinforcing bars used in concrete construction varies greatly, but the most common forms are shown by way of illustration in Figs. 1 and 2. In Fig. 1, the bars are shown as substantially round in cross section and in Fig. 2 rectangular. The bars usually have cross corrugations or bumps to

prevent longitudinal displacement in the concrete.

For horizontal building elements, such as joists and beams, there are usually "truss" bars, that is to say, bars which are bent upwardly near their ends and which lie alongside substantially straight bars, the intermediate portions of the truss bars and all portions of the straight bars preferably lying close to the bottom of the beam or joists, slightly above the bottom surface thereof. All portions of the reinforcing bars are, of course, buried in the concrete when poured.

There are a large number of devices on the market made out of heavy wire or pressed metal for maintaining the desired relationship of the horizontal portions of the bars above the false-work. Builders, naturally, find the more inexpensive chairs or supports more desirable, providing these have sufficient strength, since after their original use in maintaining the bars in place, they are left in the concrete. Most of the sheet metal devices are either too weak to stand the strains of use, or are too expensive, the latter being largely because of the necessary waste in forming them from sheet stock. Chairs made from bar stock, such as wire, on the other hand, may be made substantially without any waste, but it has been found very difficult to form chairs made of wire or bar stock which will have the necessary stability and compactness, unless a very high grade of wire is used, or stock of such large cross section that it is prohibitive, both from the standpoint of bending machine cost and material cost. This has been partly due to the fact that the chairs have been made with very sharp bends and/or close loops for greater compactness, i. e. reduction in storage and shipping cost. If the construction results in sharp bends, then the metal of the chairs is weakened and must, therefore, be made heavier than would be ordinarily necessary. Close loops present difficulties in bending, that is, run up the die and machine installation and operation cost in manufacture. With chairs made in accordance with my invention, substantially all the difficulties are overcome; the manufacturing and material cost is cut down because there are no close loops or sharp bends, and further, the device is entirely satisfactory in serving its function, that is to say, providing for properly spacing the bars, providing adequate strength for holding them in the desired relation to the false-work and providing against the chairs being tipped over when the bars are placed thereon.

The chair shown in the drawings is on the order of that shown in the prior patent to James Reynolds et al., No. 1,615,651, issued January 25, 1927. This chair, however, was expensive to produce by reason of the num-

ber and closeness of the bends in the wire or stock necessary to produce a single chair.

The chairs in accordance with my invention are made up in units, providing for the support of two bars side by side, but obviously the provision for supporting a greater number of bars on one chair, by extending the chair, may be made. There is a single substantially horizontal portion of the stock formed at its ends to provide a suitable rest, and there is a vertical arch formation substantially centrally of the substantially horizontal portion, which provides for spacing the bars the desired distance as well as lends vertical strength to the chair. The preferred chair is illustrated in Fig. 1.

The central arched bend or loop in the wire stock, which is upwardly, is indicated at 1 and the adjacent substantially horizontal or bar engaging portions, are indicated at 2. 70 The bends adjacent the horizontal portions which start the chair rest formation are indicated at 3. Continuing from the bends 3 and outwardly from the horizontal portions 2, the wire extends upwardly into open loops, each comprising a substantially vertical stretch 4, a crown bend 5 and a diagonally extending downward stretch 6. The extreme ends of the wire, indicated at 7 and 7', extend horizontally as at 8, to lie substantially crosswise of the substantially horizontal bar supporting portions 2, and at the required distance below these portions 2 to hold the bars the desired distance from the false-work. One of the horizontal ends extends from its bend in one direction transverse to the portions 2, and the other end in the opposite direction to minimize the tendency of the chair to rock sidewise.

The manner in which the bars are supported is best shown in Figs. 1 and 2. In Fig. 1, substantially round bars B are shown as lying on the horizontal portions 2 while spaced and maintained in position by the arch effect at 1 and the upward loops at 4-6. Fig. 2 shows, diagrammatically, a pair of bars at B' which are substantially rectangular in cross section, these making substantially line contacts with the horizontal portions, as shown.

If desired, the portions 2 may not be truly horizontal, but may dip downwardly adjacent the arch formation 1, as indicated in broken lines at 2' in Fig. 2, in order to more definitely space bars which are round or rounded in cross section. This is illustrated partly by way of showing what is meant in the description and claims by generally horizontal or substantially horizontal.

The arch formation 1, extending upwardly from the normal plane of the bar engaging portion, has substantially a crown top and sloping sides, which present a sufficient angle to effect a camming action upon any reinforcing bar placed too near the center of the bar.

engaging portion, thus insuring the correct placing of the bar.

It will be seen that the central arch at 1 lends rigidity to the generally horizontal portion of the chair, including the portions 1 and 2, to keep the weight of the bars from centrally deflecting the supporting portion of the chair downwardly. Such deflection would of course allow the supported bars to sag and possibly touch the false-work, which is obviously highly undesirable. The bends at 3 and 5 may be on comparatively long radii, without diminution of their supporting effect or material increase in the size of the chair, likewise, the bend at 8. By reason of one stretch 6 inclining downwardly from the generally horizontal portions of the chair in one direction and the other stretch 6 inclining downwardly in the opposite direction, together with the oppositely bent ends 7, the chair is hard to tip over in either direction when once the portions 7 are placed on the false-work, shown diagrammatically at F.

In the preferred method of constructing the chair, starting with a blank W, indicating a suitable length of wire or rod, the wire may be held as in a die which will fairly closely embrace those portions of the wire which are to become the horizontal stretches 2. The arch effect 1 and the bends at 5 including the formation of the wire at its proper angle at 6, may be formed all by one movement, as of a press, the actual time of application of bending force being determined by the draw of the wire.

A second operation, as of tools acting oppositely and at right angles to the previously acting members, will result in turning in the ends 7 from their previous positions at 7a so that they lie substantially parallel to the portions 2 and substantially in mutual alignment. Fig. 7 illustrates the blank at the stage of formation above described, when viewed at right angles to Fig. 6, as in plan. The portions 1, 2 and 8 of the blank may now be gripped firmly in the same or another die and a pair of tool members may now be caused to approach the end portions 6-7 from opposite directions and turn these portions at right angles to the plane of the portions 1-2-4 which will result in twisting the connecting portion 4 between the bends 3 and 5 through an angle of approximately 90 degrees. This twisting, as a matter of fact, does not effectively weaken the chair, since substantially all the strains imposed on the portions 8 are vertical strains.

It is to be understood that the method of forming the article shown illustrates simply the preferred method, and obviously, insofar as the claims to the article itself are concerned, any other suitable method of formation may be employed. Further, the sequence of operations described may be varied some-

what while keeping within the terms and spirit of the appended method claims.

From the above description, it will be seen that I have provided a supporting device for concrete reinforcing bars and the like which is very simple in character, very easily formed and which is particularly well suited to serve the intended purpose. It will be seen that the various bends in the stock to form the device are comparatively open; likewise, the loop formations therein do not call for the wire or stock touching on itself or approximately touching at any point, and that the finished article will remain upright to support concrete reinforcing bars or the like under the usual adverse conditions surrounding concrete construction. Further, it will be seen that I have provided a method which is simple, economical and effective and which may be used in forming articles of the general character shown made from wire or rod.

I claim:

1. A concrete reinforcing bar chair, comprising a single piece of elongated metal stock having a vertically disposed rounded arch formation substantially at the mid point thereof, bar supporting depressed portions adjacent the arch, and upwardly extending loops joining the depressed portions, said loops each having a substantially vertical side and an outwardly inclined side, the outwardly inclined side and the respective said vertical portions lying in planes substantially normal to a vertical plane passing through the arched formation, the ends of said stock extending in said normal planes respectively in opposite directions to provide a rest support for the chair.

2. A method of constructing a supporting member from elongated metal stock, comprising imparting two spaced open loops in a suitable section of such stock all in one plane, bending the remote ends of said stock toward each other into substantial alignment, and then twisting the two loops thus formed out of their respective planes and in opposite directions to cause the said ends and the loops to lie in supporting relation to the intermediate portions connecting the loops and transversely thereof.

3. The method of constructing a supporting member from elongated metal stock, comprising the steps of imparting two spaced open loops in a suitable section of such stock, both substantially in one plane, and then twisting the two loops out of their respective planes to cause the looped portions of the stock to lie substantially parallel to each other in planes transverse to their original plane.

4. The method of constructing a concrete reinforcing bar chair, comprising imparting two spaced loop-like bends to a suitable length piece of elongated metal stock, said bends lying substantially in the same plane,

forming the remote ends of the stock to provide ground engaging portions integral with and adjacent the loops and then twisting the loops and ends substantially about the axes 5 of respective side portions of the loops through angles of approximately 90 degrees.

5. A supporting member for concrete reinforcing rods, comprising a single piece elongated metal bar, each end of said bar 10 being bent to form supporting legs, the legs comprising a horizontal portion adapted to lie on the supporting surface and a portion extending upwardly at an acute angle to the horizontal portion, both of said portions 15 lying within a vertical plane which is perpendicular to a vertical plane through the bar, the upwardly extending portion of the legs lying on opposite sides of said vertical plane through the bar, the connecting portion 20 of the bar between said supporting legs being lower than the top of said upwardly extending portions, and having an upward bend centrally of said legs, presenting two oppositely downwardly diverging surfaces, 25 whereby concrete reinforcing rods placed anywhere on the connecting portion of the bar will seek the lowest level and thereby become correctly placed.

6. A chair for concrete reinforcing rods, 30 comprising an elongated metal bar bent at each end to provide supporting legs, each leg comprising a base portion and a portion extending upwardly at an acute angle to said base portion, the aforementioned acute 35 angles being on opposite sides of a vertical plane through said metal bar, so that when looked at from either end of the chair the two legs would seem to form an isosceles triangle, the upwardly extending portions forming the 40 two equal sides and the two base portions overlapping to form the base, the connecting portion of the bar between said legs being bent to a plane lower than the top of said upwardly extending portions, and having an 45 upwardly inverted flat V-shaped bend centrally of said legs, whereby concrete reinforcing rods placed anywhere between the top part of the V-shaped bend and the legs will seek the lowest level and thereby become correctly placed.

In testimony whereof, I hereunto affix my signature.

THEODORE SCHMITT.
